UNITED STATES PATENT OFFICE.

CLARK TAYLOR BROWN, OF NEW YORK, N. Y.

TYPE-WRITER.

No. 843,997.

Specification of Letters Patent.

Patented Feb. 12, 1907.

Application filed January 24, 1906. Serial No. 297,554.

To all whom it may concern:

Be it known that I, CLARK TAYLOR BROWN, a citizen of the United States of America, and a resident of the borough of Brooklyn, in the city of New York, county of Kings, and State of New York, have invented certain new and useful Improvements in Type-Writers, of which the following is a specification.

My invention relates to a construction of type-bars in that class of type-writers wherein a series of type-bars are mounted to strike at a common printing-point and are guided near their heads by a guide with a flaring slot, into which each type-bar strikes as it approaches the printing-point.

The object of the invention is to provide means whereby in event of a type-bar being held in the guide while a second type-bar is being operated that the second bar will be prevented from entering the space on either side between the first type-bar and either side of the flaring slot in the guide, so as to become wedged.

In the accompanying sheet of drawings, which forms a part of my application, Figure 1 is a vertical section through the type-bar-supporting segment of a type-writer, showing two type-bars, a type-bar guide, and a platen constructed in accordance with my invention; and Fig. 2 is a top view of the guide at a section through two type-bars on the line II II of Fig. 1.

My invention is illustrated in connection with a machine of the well-known Underwood type, wherein type-bars are mounted in a segment of less than a half of a circle, so as not to obstruct a view of the writing as it is written, as set forth in Reissue Letters Patent of the United States No. 12,252, dated

August 2, 1904.

A segment B, which is incorporated in the framework of the type-writer, affords pivotal support for all of a series of type-bars C C'; but owing to the confined pivotal space permissible for each type-bar a guide D is supported from the segment in proximity to the printing-point p of a platen E. The guide has a slot into which the type-bars strike.

The purpose of the guide is to accurately position the heads of the type-bars at the printing-point. The guide has a flaring slot, between the sides of which the type-bars are guided, the slot being wider at the end at which the type-bars enter than the thickness of the type-bars and narrowing toward its

other end to a width equal to the thicknesses of the type-bars at the points engaged by the guide, so that each will be properly positioned by the guide at the moment of printing. 60 This guide is necessary, particularly in a machine having all the type-bars pivoted in an arc of less than half of a circle, because there is insufficient space to accurately position the type-heads at the printing-point by means 65 of the pivotal supports. With such a guide and type-bars such as have been heretofore constructed occasionally when writing rapidly and a type-bar is in place in the guide a second type-bar may be operated, with the 70 result frequently that the second type-bar is driven into the V-shaped space between the first type-bar and one side or the other of the slot in the guide, and both type-bars become 75 so wedged that some time and effort is necessary to clear them. Possibility of such wedging is eliminated by the construction herein set forth, which consists in the provision of a broad spot s at a point on the back of each type-bar near its type-head, where if 80 the type-bar is in the guide and a second type-bar is operated the second type-bar will strike the broad spot or anvil on the first bar, and the second type-bar cannot pass between the side of the first type-bar at either 85 side of the slot in the guide and become wedged.

It is not necessary for the function above set forth that the broad spot should be exactly opposite the guide and actually cover 90 the wide end of the slot in the guide, but only that it should appear to do so when viewed in the direction of the shank of the type-bar when in the guide, as illustrated in Fig. 2, sufficiently to prevent the entrance of 95 a second type-bar.

What I claim as new, and desire to secure by Letters Patent of the United States, is—

1. In a writing-machine, the combination with a platen of a guide with a flaring slot in 100 proximity to the printing-point of the platen, and a series of type-bars mounted to strike into the slot, the back of each type-bar having a width at a point adjoining the head and clear of the guide sufficient when the type-bar is in the guide to prevent the entrance 105 and wedging of a second type-bar, substantially as described.

2. In a writing-machine, the combination with a platen of a guide with a flaring slot in 110 proximity to the printing-point of the platen, and a series of type-bars mounted to strike

into the slot, the back of each type-bar having a width at a point adjoining the head and between the head and type-bar pivot sufficient when the type-bar is in the guide to prevent 5 the entrance and wedging of a second type-bar, substantially as described.

3. In a writing-machine, the combination with a platen of a guide with a flared slot in proximity to the printing-point, and a series 10 of type-bars mounted to strike in the slot, each of the type-bars having a portion of its

rear thicker than the front portion of the bar entering the slot, and of sufficient width when the type-bar is in the guide to prevent the entrance therein of a second type-bar.

Signed by me at New York, N. Y., this 22d day of January, 1906.

CLARK TAYLOR BROWN.
